ARRANGEMENT FOR AMPLITUDE MODULATION

Rudolf Urtel, Berlin, Germany, assignor to Tele-funkens Gesellschaft für Drahtlose Telegraphie m. b. H., Berlin, Germany, a corporation of Germany

Application August 12, 1936, Serial No. 95,519
In Germany August 12, 1935

12 Claims. (Cl. 178—7.1)

The invention relates to an arrangement for amplitude modulation in which the value of the sum of two alternating currents of equal frequency is formed, and one or both partial currents are varied about an average value by one of several modulation voltages by means for influencing the degree of amplification of a controlled discharge tube. Such modulation circuits which may be designated as tube bridge circuits, were found in the past to be extremely unstable in operation. Therefore in practice, such tube bridges for modulation purposes have not found use, and other modulation arrangements have been resorted to. This invention overcomes the instability hitherto observed in tube bridging circuits, which is due to the amplifier tubes proper, and which apparently has its origin in the fluctuations of the emission of the tube cathodes. These fluctuations are however small when measured on the mean emission amperage of the cathode. But in tube bridges they produce a disturbing phenomenon because of the fact that the difference current of the bridge on which the modulation arrangement principally depends, is comparatively much more influenced by the said fluctuations in the emission than the plate current, since the alternating plate currents are substantially compensated. On the basis of this experience, it is proposed in bridge circuits used for modulation purposes, that the output voltages of the bridge be amplified, detected, and modulation potentials filtered out, and to apply the direct potential obtained to the electrode of one or both controlled discharge tubes of the modulation arrangement which electrode influences the amplification of the alternating currents.

Several embodiments of the invention are shown in the drawing wherein

Fig. 1 shows a schematic circuit showing the means and method of stabilizing tube bridges;

Fig. 2 shows a graphical analysis of the circuit operation for explaining the invention;

Fig. 3 shows a modification of one of the circuit elements of Fig. 1 useful for television;

Fig. 4 shows a block diagram of a modification of my invention where a plurality of modulating potentials are used; and

Fig. 5 shows a block diagram of the invention applied to variable amplitude carrier transmitters.

In Figure 1, items 10 and 11 designate two tetrodes, 12 is a transformer and 13 to 16 are direct voltage sources. There is inserted in the common plate circuit of the two tubes, a paral-

lel resonance circuit 8 tuned to the carrier frequency applied to the primary winding of the transformer 12. Item 17 represents a high-frequency amplifier which amplifies the entire band, and to which a detector 19 is coupled by a transformer 18. The detector circuit contains a resistor 20, a condenser 21 and a further arrangement serving for filtering out the modulation potentials and consisting of a condenser 22 and a resistor 23. The point P is connected to the control grid 1 of the tetrode 11 in series with a compensation voltage source 24.

The arrangement according to Fig. 1 operates such that there will be applied to the control grid 1 of the tetrode 10 the modulation frequencies corresponding to the brilliancy of the picture point, and which may be derived for instance from any picture scanning means. At the two control grids 2 situated next to the anode, alter-

nating potentials exist in opposite phase which are taken from the two ends of the secondary winding of the transformer 12. Disregarding at first the control action proposed in accordance with the invention, and thus assuming that the grid 1 of tube 11 to be at constant potential

relative to the cathode whereby in this case the grid 1 is connected to the voltage divider connected to the battery 15, the arrangement operates in such way that owing to phase opposition

of the potentials applied to the two grids 2, the alternating anode currents compensate each other in the common plate circuit if the two grids 1 have the same potentials. If however, for instance at grid 1 of tube 10 a higher positive potential appears than at grid 1 of tube 11, then

in the common anode circuit, the alternating anode current supplied by the tube 10 predominates, so that at the parallel resonance circuit there appears a voltage having carrier frequency,

whose amplitude depends upon the potential difference of the two grids 1. The same action will also take place for variation in the emission of the cathode of the one of the two tubes, the characteristic of that tube being displaced. The remaining circuit represented in Figure 1 now

operates in such manner that such fluctuations in the emission of the one tube is rendered ineffective by corresponding potential displacement of the grid 1 of the tube 11. It will be appreciated that the fluctuations in tube emission take

place relatively slowly compared with the modulation frequencies. In the high-frequency amplifier 17, the voltage appearing at the parallel resonance circuit will be amplified, then detected

by the arrangement 19 to 23 showing a rectifier 55

and filter, and deprived of the modulation frequencies by suitable choice of constants for the condensers 21 and 22 and resistors 20 and 23. The potential appearing at point P thus varies in accordance with the variable emission of the two tubes. This potential is applied, through a compensation voltage source 24, to the grid 1 of tube 11, and hence influences the amplification of this tube such that the fluctuation of the input potential of the amplifier 17 produced by variation in the emission will be compensated almost entirely. Under these conditions changes of the grid 1 potential in the tube 10 serves to produce a modulated carrier wave which is proportional to the difference between the anode current of the tubes 10 and 11. It will be noted in this respect that when the bridge is balanced, the carrier wave produces plate currents in phase opposition in the two tubes 10 and 11, but inasmuch as the anodes of the two tubes are connected together, the resultant current flowing through the tuned circuit 8 is zero since when the plate current of the tube 10 increases, the plate current of the tube 11 decreases in equal amount so that the sum remains constant. When the grid 1 of the tube 10 has applied modulating potentials thereto, the balance is destroyed and if the modulating potentials are of positive polarity, the plate current of the tube 10 increases so that the total increase of the plate current of the tube 10 is greater than the total change in an opposite sense of the plate current of tube 11, and consequently, there will appear a voltage across the tuned circuit 8 which is proportional to the voltage applied to the grid 1 of tube 10. This instantaneous change in voltage, however, is not effective to rebalance tube 11 since the filter constants of the elements 20-23 are chosen to suppress high frequency components.

The functioning of the circuit according to Fig. 1 can be explained graphically by means of the tube characteristics shown in Fig. 2. In this figure, there is shown in relation to the voltage e_1 at the grid 1 of tube 11, the input voltage e_2 of the high-frequency amplifier 17. The bridge may be completely balanced at the value e_1 at the grid of tube 10. Therefore, the carrier-frequency potential at the parallel resonance circuit is zero. For lower, or higher values of e_1 the equilibrium of the bridge is disturbed, so that a carrier frequency appears at the parallel resonance circuit having the amplitude shown as ordinate of the line course a, b, c . At another emission current of the one of the two tubes other values of e_1 are required to establish the equilibrium of the bridge, namely the values e_1'' and e_1''' respectively, and correspondingly the line course for the bridge is a'', b'', c'' , and a''', b''', c''' , respectively. In assuming that the voltage at grid 1 of tube 11 would have the value E_1 continuously, at a variation of the emission of the one tube, the carrier frequency amplitude at the input of the amplifier 17 would vary, i. e. the voltage e_2 would vary between the values e_2'' and e_2''' , if however as proposed in accordance with the invention, a potential is applied to the grid 1 of tube 11, consisting of the compensation voltage e_1 and of the voltage e_3 at point P, then only an unlike lower fluctuation of the voltage e_2 occurs. This can be readily seen when marking the voltage e_2 at the abscissa in Figure 2, and observing that the cotangent of angle β corresponds to the ratio between the voltage e_3 and the voltage e_2 .

Now the balance point of the bridge i. e. the

working point on the bridge line can be adjusted in a simple manner by varying the value of the compensation voltage e_1 . Figure 2 shows that at a decrease of the value e_1 , the working point moves downwards on the right hand branch of the bridge characteristic, and moves upwards with an increase of e_1 .

When applying the described modulation arrangement to a television transmitter, it will be desirable to apply to the grid 1 of tube 10 only a modulation potential which corresponds to the alternating component of the picture brilliancy, and to vary the compensation potential e_1 in accordance with the average picture brilliancy. This can be accomplished by inserting in place of the compensation voltage source 24 in Figure 1, the circuit shown in Figure 3. Herein, item 25 designates a photocell on which the entire picture to be transmitted is projected, item 26 is a D. C. voltage source, and 27 is a resistor. Thus the photocell 25 integrates the brilliancy values of the entire image, and the voltage drop through resistor 27 thus corresponds to the average picture brilliancy.

A bridge arrangement of the type described also affords the transmission of other signals in an especially simple manner than those corresponding to the picture brilliancy, such as for instance line and picture alternation signals. If the line and picture alternation pulses are to be sent out by means of a shorter or longer complete interruption of the carrier wave, it is only necessary to take care that for the transmission of completely black picture points, the bridge arrangement is not modulated to the value $e_1=0$, and for sending out these special additional signals such as synchronizing pulses, it is only necessary to disconnect from the bridge the high frequency feed.

This may be accomplished for instance by means of the circuit shown in Figure 4. Herein, the tube bridge is designated by 28, the carrier wave generator is represented by 29, and the keying stage is designated by 30, and may consist for instance of a hexode which has the keyed potential applied to one of its control grids. Item 31 is a generator for the synchronizing pulses, and 32, 33 are saw tooth generators of a cathode ray picture scanning means 34. The currents furnished by this generator are fed across an amplifier 35 into the grid 1 of tube 10 in the bridge in Figure 1. To simplify the illustration, the control arrangement for the continuous adjustment of the working point of the bridge is omitted in Figure 4.

The modulation arrangement proposed according to the invention may also be utilized for the purpose of the so-called auto-modulation. By this is meant a modulation method in which for the purpose of saving transmitter energy, the high frequency amplitude is always adjusted to a value approximately proportional to the amplitude of the modulation voltage. Thus at a lower modulation voltage, the carrier frequency amplitude is small and vice versa. To this end the compensation voltage and hence, the carrier frequency amplitude is to be rendered dependent upon the amplitude of the modulation voltage. A corresponding arrangement is shown in Figure 5. Herein, just as in Figure 4, item 28 represents the bridge arrangement, and just as in Figure 1, item 17 is the high frequency amplifier, and 19 to 23 represent the detector arrangement. In addition Figure 5 contains a further detector 36 by which the modulation voltage will be detected,

and whose output terminals are connected to a resistor 37 at which the compensation voltage appears.

What I claim is:

- 5 1. In a balanced bridge modulator, the method of stabilizing the balance of the bridge against fortuitous unbalancing, which comprises producing energy in accordance with fortuitous unbalancing of the bridge, and balancing the bridge 10 with the produced energy.
- 15 2. In a balanced bridge modulator, the method of stabilizing the balance of the bridge against fortuitous unbalancing, which comprises deriving from the bridge carrier wave energy modulated by both signalling energy and spurious energy, deriving energy from the last mentioned energy representative only of the spurious modulated energy, and balancing the bridge with the second 15 mentioned derived energy.
- 20 3. In a balanced bridge modulator, the method of stabilizing the balance of the bridge against fortuitous unbalancing, which comprises deriving from the bridge carrier wave energy modulated by both signalling energy and spurious energy, rectifying the derived carrier wave energy, filtering out a component of the rectified energy representative only of the spurious modulated energy, and balancing the bridge in accordance 25 with the filtered component of energy.
- 25 4. A stabilized balanced bridge modulator comprising means for producing energy in accordance with fortuitous unbalancing of the bridge, and means for balancing the bridge with the produced energy.
- 30 5. A stabilized balanced bridge modulator comprising means for deriving from the bridge carrier wave energy modulated by both signalling energy and spurious energy, means for deriving energy from the last mentioned energy representative only of the spurious modulated energy, and means for balancing the bridge with the second 35 mentioned derived energy.
- 35 6. A stabilized balanced bridge modulator comprising means for deriving from the bridge carrier wave energy modulated by both signalling energy and spurious energy, means for rectifying the derived carrier wave energy, means for filtering out a component of the rectified energy representative only of the spurious energy, and means for balancing the bridge in accordance with the filtered component of energy.
- 40 7. In a balanced bridge modulator, the method of stabilizing the balance of the bridge against fortuitous unbalancing, which comprises deriving from the bridge carrier wave energy modulated by both signalling energy and spurious energy, rectifying the derived carrier wave energy, filtering 45 out a component of the rectified energy representative only of the spurious energy, and means for balancing the bridge in accordance with the average value of the signalling energy.
- 45 55 8. A stabilized balanced bridge modulator comprising means for deriving from the bridge carrier wave energy modulated by both signalling energy and spurious energy, means for rectifying the derived carrier wave energy, means for filtering out a component of the rectified energy representative only of the spurious energy, supplying a source of constant energy, and feeding the filtered component of energy in series with the supplied source of constant energy to the bridge to balance the bridge for the spurious energy.

5 9. A stabilized balanced bridge modulator comprising means for deriving from the bridge carrier wave energy modulated by both signalling energy and spurious energy, means for rectifying the derived carrier wave energy, means for filtering out a component of the rectified energy representative only of the spurious energy, supplying a source of constant energy, and means for feeding the filtered component of energy in series with the supplied source of constant energy to the bridge to balance the bridge for the spurious energy.

10 10. A stabilized balanced bridge modulator comprising means for deriving from the bridge carrier wave energy modulated by both signalling energy and spurious energy, means for rectifying the derived carrier wave energy, means for filtering out a component of the rectified energy representative only of the spurious energy, supplying a source of constant energy, and means for feeding the filtered component of energy in series with the supplied source of constant energy to the bridge to balance the bridge for the spurious energy.

15 11. In a balanced bridge modulator, the method of modulating carrier wave energy, which comprises the steps of adjusting the bridge to a predetermined balance, deriving energy from the bridge representative only of spurious modulated energy, re-establishing the balance of the bridge in accordance with the derived energy, and photoelectrically altering the balance of the bridge in accordance with the integrated illumination of an optical representation to be transmitted.

20 12. A balanced bridge modulator comprising means for adjusting the bridge to a predetermined balance, means for deriving energy from the bridge representative only of spurious modulated energy, means for re-establishing the balance of the bridge in accordance with the derived energy, and means for photoelectrically altering the balance of the bridge in accordance with the integrated illumination of an optical representation to be transmitted.

25 13. The method of operating a balanced bridge modulator which comprises deriving from the bridge carrier wave energy modulated by both signalling energy and spurious energy, deriving energy from the last mentioned energy representative only of the spurious modulated energy, balancing the bridge with the second mentioned derived energy, and unbalancing the bridge in accordance with the average value of the signalling energy.

30 14. A balanced bridge modulator comprising means for deriving from the bridge carrier wave energy modulated by both signalling energy and spurious energy, means for deriving energy from the last mentioned energy representative only of the spurious modulated energy, means for balancing the bridge with the second mentioned derived energy, and means for unbalancing the bridge in accordance with the average value of the signalling energy.

RUDOLF URTEL.
